J. H. STULL,
FRICTION CLUTCH,
APPLICATION FILED AUG. 12, 1915.

1,193,442.

Patented Aug. 1, 1916.

UNITED STATES PATENT OFFICE.

JACOB H. STULL, OF FREMONT, OHIO.

FRICITION-CLUTCH.

1,193,442.

Specification of Letters Patent.

Patented Aug. 1, 1916.

Application filed August 12, 1915. Serial No. 45,168.

To all whom it may concern:

Be it known that I, JACOB H. STULL, a citizen of the United States, residing at Fremont, in the county of Sandusky and State of Ohio, have invented certain new and useful Improvements in Friction-Clutches; and I do declare the following to be a full, clear, and exact description of the invention, such as will enable others skilled in the art to which it appertains to make and use the same.

My invention relates broadly to improvements in clutches and more particularly to those of the friction type.

The object of the invention is to provide a device of this class which although being of extremely simple and therefore inexpensive construction, will be highly efficient and durable and will possess a number of advantageous characteristics.

With this general object in view, the invention resides in certain novel features of construction and in unique combinations of parts to be hereinafter fully described and claimed, the descriptive matter being supplemented by the accompanying drawing wherein:

Figures 1 and 2 are respectively side and edge views of a clutch constructed in accordance with my invention; Fig. 3 is a central longitudinal section as viewed along the plane indicated by the line 3—3 of Fig. 2; Fig. 4 is a transverse section taken on the plane of the line 4—4 of Fig. 1; and Fig. 5 is a similar view as seen on the plane indicated by the line 5—5 of Fig. 2.

In this drawing which constitutes a part of the application and in which like reference characters designate corresponding parts throughout the several views, the numeral 1 indicates a rigid but rotatable friction disk provided, preferably at diametrically opposite points, with a pair of guide arms 2 which not only lie parallel to each other but to the axis of the disk. As clearly shown, the arms 2 are integrally connected to the disk 1 at one end, while the other ends of said arms are directed inwardly toward each other and are integrally joined at 3 to a hub 4, the latter being secured by a key 5 or an equivalent locking device to a shaft 6.

Disposed in axial alinement with the hub 4 and disk 1 and interposed between the arms 2 is a second and shiftable friction

disk 7, such disk being shown in the present embodiment of the invention as having ears extending from its edge at opposite points and provided with guide notches 8 which so receive the arms 2 as to allow the disk 7 to slide freely toward and away from the disk 1.

Interposed between the two disks 1 and 7 is an additional disk 9 which is rotatable independently thereof, said disk 9 being here shown as provided with a tubular hub 10 which passes loosely through a central opening in the disk 1 and which rotatably receives the shaft 6. This hub 10 may be keyed to a pulley 11 as shown in the drawings, may be secured to an additional shaft, or may itself constitute the shaft as will be obvious to those skilled in the art to which the invention relates.

Numerous devices may well be provided for shifting the disk 7 toward the disk 1 to bind disk 9 frictionally therebetween, but by preference I provide the construction now to be set forth. The disk 7 is equipped with a hub 12 which is formed in two sections, an innermost externally threaded section 12^a carried rigidly by the disk and receiving the shaft 6 loosely, and an outer ring-like section 12^b which is provided with internal screw threads engaging the external threads on the section 12^a. By this construction, the length of the hub may be varied for a reason yet to be set forth. After adjusting the length of the hub, however, it is necessary to provide some simple means for locking the two sections 12^a and 12^b against relative movement, and although this may be done in a number of ways the member 12^b is preferably split and equipped with a clamping bolt 13 whereby it may be contracted and thus held frictionally around the section 12^a.

The outer end of the hub 12 (the section 12^b thereof) bears against a thrust collar 14 which is interposed between the aforesaid hub and the hub 4, diametrically opposite points on said collar being engaged by the ends of a pair of disk-shifting levers 15 which are pivoted to ears or the like formed on the hub 4. In the present embodiment of the invention, the levers 15 are shown of such shape as to force the collar 14 toward the disk 1 when said levers are forced away from each other, and a shiftable cone 16 is provided for so actuating said levers but ob-

viously the levers may be of other formation and equivalent means may well be provided for operating the same.

When the cone 16 is shifted from the position disclosed in Fig. 2 to that depicted in Fig. 1, the collar 14 moves the hub 12 in such a direction as to cause the disk 9 to be frictionally gripped between the two disks 1 and 7, the existing friction between these 10 disks being increased by rings 17 carried by the inner faces of the disks 1 and 7, said rings being preferably though not necessarily constructed of fiber board. Thus it will be evident that a reliable connection is 15 established between the shaft 6 and the pulley 11, or between said shaft and any other device which may take the place of the aforesaid pulley. When the cone 16 is shifted to inactive position to release the 20 clutch, it is essential to provide some means whereby the numerous movable disks may be returned to their normal positions. Here again, numerous details of construction may be employed, but coil springs 18 are prefer- 25 ably interposed between the central disk 9 and the disks 1 and 7.

From the foregoing description, taken in connection with the accompanying drawings, it will be evident that although the construction of the device is extremely simple, 30 the invention will be efficient and durable and will possess a number of advantages. Among these advantages, is the unique construction for guiding the movable member 7 35 and its association with that for supporting the levers 15, and the construction of the extensible hub 12, this being a rather salient feature since by its use, the disks may be forced into proper frictional contact, re- 40 gardless of wear incurred thereby. Particular emphasis is laid upon the fact that the last named result may be obtained without varying the relation of the cone 16 and the levers 15.

Copies of this patent may be obtained for five cents each, by addressing the "Commissioner of Patents, Washington, D. C."

In the drawings, certain specific details of 45 construction have been shown for accomplishing probably the best results, and in the preceding such details have been described, but obviously I need not be restricted thereto, otherwise than to the extent to which the 50 appended claims limit me.

I claim:—

1. A clutch comprising a friction disk, a hub member spaced axially therefrom, a pair of spaced arms connecting the disk and 55 hub member and disposed parallel to the axis thereof, a second friction disk between the two arms and having guides slidable on said arms, a third disk interposed between the other disks and rotatable independently 60 thereof, and a disk-shifting lever fulcrumed to the aforesaid hub member for shifting the second disk.

2. A clutch comprising a friction disk having a central opening, a pair of spaced arms 65 projecting from said disk at diametrically opposite points and disposed parallel to the axis thereof, said arms having their ends directed inwardly toward each other, a hub to which said inwardly directed ends are 70 joined, a second disk between the two arms having notches at diametrically opposite points in its edge slidably receiving said arms, a third disk interposed between the other disks and having an axial extension 75 projecting through the opening in the first named disk, a hub on the second disk ex- tended toward the first named hub, and an operating lever fulcrumed to said first named hub for shifting the other hub 80 axially.

In testimony whereof I have hereunto set my hand in presence of two subscribing witnesses.

JACOB H. STULL.
